UNITED STATES PATENT OFFICE.

ALEXANDER K. RIDER, OF NAZARETH, PENNSYLVANIA, ASSIGNOR TO HIMSELF, C. H. DELAMATER, AND G. H. REYNOLDS.

IMPROVEMENT IN VALVES FOR STEAM-ENGINES.

Specification forming part of Letters Patent No. 78,483, dated June 2, 1868.

To all whom it may concern:

Be it known that I, ALEXANDER K. RIDER of Nazareth, in the county of Northampton, in the State of Pennsylvania, have invented certain new and useful Improvements in the Valve-Gear for Steam-Engines; and I do hereby declare that the following is a full and exact description thereof.

My invention is intended more particularly for steam pumping-engines, steam-hammers, and the like varieties of engines, in which no cranks or equivalent working parts are employed. It provides for operating the valves with great rapidity and certainty, with simple mechanism, and without the necessity for any mechanical connection.

I will first describe what I consider the best means of carrying out my invention, and will afterward designate the points which I believe to be new therein.

The accompanying drawings form a part of this specification.

Figure 1 is a central longitudinal section. Fig. 2 is a cross-section on the line S S of Fig. 1. Fig. 3 is a cross-section on the line T T of Fig. 1. Fig. 4 is a longitudinal section on the crooked line U U in Fig. 2. In this figure the piston has just arrived at the left extreme of its motion, and the valve has just been thrown to the right, so as to induce a return motion. Fig. 5 is a corresponding section of a portion, showing the parts in the position which they assume when the piston has arrived at the opposite end of the stroke. The valve has in this figure just been thrown to the left.

Similar letters of reference indicate like parts in all the figures.

A is the main body of the cylinder, and B is the piston. There are the ordinary cylinder-ports *a a* and the ordinary exhaust-port *a'*. In addition to these cavities there are two small chambers, *C¹ C²*, connected with the exhaust-passage, and provided with ports which I term "master-valves" *D¹ D²*. These valves are provided with internal passages *d¹ d²*, and the chambers *C¹ C²* are connected by small passages with the interior of the main cylinder, and with the interior of the steam-chest or main-valve chamber E, as will be described below.

G is the slide-valve of a semi-cylindrical

form. It has a cavity on its under face, and is equivalent in function to the ordinary cup-valve. *g g* are stout necks connecting this valve with pistons *G¹ G²*. I prefer to form the valve and pistons with their necks in a single piece, but it is not essential. The entire lower side of the valve-chamber is finished by boring, so as to form a true cylindrical surface; and the chamber is cylindrical throughout, except for a small space in the middle, as represented. The pistons *G¹ G²* are adapted to fill the chamber, so as to work nearly or quite steam-tight. The lower face of the valve G is turned, and is finished by scraping or otherwise, to form a steam-tight contact with the semi-cylindrical lower side of the valve-chamber. This mode of finishing the surfaces of these rubbing parts allows a tight fit to be produced with very little expense.

H is a shaft, which may be provided with a stuffing-box. (Not represented.) It aids in starting the engine by means of the arm *h*, which works in a corresponding cavity in the back of the main valve G. The hollow throat in the bottom of the valve performs the same function relatively to the ports on the semi-cylindrical surface as the hollow throat of the ordinary flat slide-valve performs relatively to the ports of ordinary engines.

Each of the master-valves *D¹ D²* has three diameters at different points, as represented. The largest part forms a steam-tight or nearly steam-tight contact with the interior of the chamber. The next smaller diameter is sufficiently smaller to afford an annular area for the action of the steam to move itself, and also to form a passage for the admission of steam to move the main valve. The smallest diameter forms a steam-tight or nearly steam-tight fit in the cylindrical passage which leads to the exhaust. The position which the master-valves maintain during the greater portion of the time is at the extreme inner end of their traverse. In this position the shoulder where the smaller part changes to the intermediate size serves as a puppet-valve, and increases the tightness with which the passage to the exhaust-port is stopped.

In Fig. 1 the piston is moving to the right, the strong steam from the valve-chamber entering freely on the left side of the piston, and

the exhaust escaping freely from the right side of the piston. The necks g g are so much smaller than the pistons G^1 G^2 that the steam flows readily through the cavity thus provided.

The provision for operating the main valve through the medium of the master-valves is worthy of special description. There is one passage from each master-valve chamber into the main-valve chamber, and there are two passages from each master-valve chamber into the interior of the main cylinder. Confining our attention for the present to the right end of the cylinder, x designates the passage between the main-valve chamber and the master-valve chamber, while y and z designate, respectively, the two passages between the master-valve chamber and the interior of the cylinder, the passage z being close to the end of the cylinder, and the passage y being situated a little more than the thickness of the main piston therefrom.

As the main piston stands in Fig. 1, both the passages y and x are exposed only to exhaust-steam. As the piston moves to the right it covers the passage y without producing any effect; but when, by the close approach of the main piston B to the end of its stroke, it uncovers the passage y , and exposes it to the live steam, (the position indicated in outline in Fig. 1,) the strong steam flows up through the passage y , fills the annular chamber around the master-valve D^2 , and throws this little valve to the right. This movement uncovers the passage x , and exposes it to the live steam, which, flowing through it, acts against the outer end of the valve-piston G^2 , and throws it and its attachments very rapidly to the left. This latter movement, as will be readily understood, entirely reverses the action of the steam upon the main piston B, admitting the strong steam from the valve-chamber to the right side of this piston, and exhausting the steam from the left side. This exhaust action also allows strong steam, which had just gone up through the passages y and x , to flow back again. The strong steam, filling the main cylinder on the right side of the piston, flows up through the passage z , and, acting against the end of the sub-valve D^2 , moves it to the left, thus restoring it to its original position, (that represented in the drawing,) and the main piston B commences to move to the left under the ordinary conditions which obtain in steam engineering—that is to say, the full pressure of the steam is exerted on the right side of the piston, and the left side is free to exhaust into the atmosphere, or into a condenser, if such be employed.

The same construction and the same arrangement obtain at the left end of the cylinder. As the main piston B approaches either end of the cylinder the master-valve at that end (which is previously in equilibrium) is thrown actively by the admission of steam

into the annular space, and on moving it uncovers the port or passage x , admits steam against the end of the valve-piston, and throws the main valve, immediately after which the master-valve returns to its original position at the inner extreme of its motion. By the change in the conditions in which the steam is admitted to the main cylinder the passage through the interior of the master-valve by the latter movement becomes available to discharge the steam from the end of the valve-piston, so that the main valve and its pistons are in equilibrium, both ends being open to the exhaust for nearly the whole period. It is only subjected to the action of steam on either end alternately for a very short space of time at the moment when the change takes place.

The proportions and forms of the parts may vary within wide limits. I have represented the master-valves and their chambers as mounted a little one side of the center, or of the line between the axis of the main-valve chamber and the axis of the main cylinder. I have represented the main ports as being in their ordinary central position. It may be preferable, for some reasons, to arrange the main ports a little one side of their central position, so as to accommodate the master-valves and their chambers and passages by placing them more nearly in the central position. Many such changes in position and many changes in the form and weight of the parts may be made without materially impairing the useful effect of my invention. I prefer, however, to make the master-valves very small—considerably smaller in ordinary practice than are here represented. The smallness of the weight of these actively-moving parts avoids any injurious jerk or concussion from a high rate of speed. It allows my engine to operate very rapidly without serious noise. I have tested my steam-pump as high as two hundred revolutions or double strokes per minute without injury, and without any sensible concussion beyond a slight clicking sound.

In that experimental engine the main cylinder has a bore of four inches. The main-valve chamber has a bore of one inch and a half, and the master-valve chambers have a bore of three-eighths of an inch. The stems which lead to the master-valves and the contracted passage leading to the exhaust are only one-fourth of an inch in diameter, and the holes through the master-valve are only one-sixteenth of an inch in diameter. I consider it important to cushion the steam in the ends of the main-valve chamber, to bring the main valve and its pistons to rest gradually. I effect this by contracting the passage for the escape of the steam from the master-valve.

i^1 i^2 are bushings screwed into the passages d^1 d^2 for the purpose of still further contracting the area of the passage. In my experimental engine I have thus contracted the pas-

sage to one-twentieth of an inch in diameter. The precise area of this passage, as also the magnitude of all the important ports, may be modified as experience shall determine. I find that the dimensions above given serve very well with my small engine. I found, upon contracting the diameter of the passage by bushings i^1 i^2 to much less than one-twentieth of an inch, the main valve would not throw to its full and proper extent, while an enlargement of the hole much beyond one-twentieth of an inch, or the omission of the bushing altogether, allowed the main valve and its connected pistons to strike against the ends of their chambers.

I propose to introduce a block of wood, or spiral or other spring, or a mass of lead or soft metal, either in the ends of the chambers or in the corresponding faces of the piston, or in each, in order to deaden the concussion when such occurs from any cause. I find a liability to concussion in starting when the ports are cold, and consider the provision just referred to mainly valuable in such contingencies.

The outer end of the shaft H is square, to allow the application of a wrench or handle, by means of which the main valve can be thrown from one end to the other by hand in warming the engine preparatory to starting. I prefer to apply a permanent handle on the end of this shaft, and to make the cavity in which the end of the arm h works of such length that the valve can be thrown its full extent in one direction or the other without turning the shaft H.

I can, by modifications of the construction and arrangement, and by varying the proportions of my ports and passages, so work the water-valves, and also the main valve, that they shall stand under the pressure of the live steam at the end during the most part of the time, and be kept by a brief period in exhaustion. This will be the opposite, in this respect, of the conditions above described, wherein these ports stand most of the time under the pressure only of the exhaust-steam, and are exposed only for very brief periods to the pressure of the strong steam.

I prefer the arrangement which I have represented; but either may be used without departing from the principle of my invention.

My invention is substantially involved in any modification of these parts where the motion not only of the main valve, but also of the master-valves, is accomplished by the action of the steam itself, without intermediate mechanism.

Some of the advantages due to certain features of my invention may be separately enumerated as follows:

First, by reason of the fact that my master-valves D¹ D² are furnished with the passages y and z, I am able to throw the master-valve, and thus ultimately the main valve, by the action of the steam itself, without any mechanical connection, and to effect this with rapidity and certainty greater, I believe, than is obtained with complicated and expensive constructions.

Second, by reason of the fact that my passages to the master-valve are contracted to such a caliber as will allow the exhaust-steam to escape from the ends of the main-valve chamber with only a limited speed, I am able, while insuring a complete emptying of the said chamber at each end, to so modify the current which escapes before the piston when the valve is suddenly thrown by the steam as to effectually cushion and soften the concussion without preventing the valve from making its full throw, and to do this without in any wise affecting the velocity with which the live steam is admitted to act on the valve-piston, because the live steam flows through other and independent passages, which may be as much larger as shall be found desirable.

Third, by reason of the fact that my cup-valve G has a cylindrical surface, and is reciprocated back and forward longitudinally of the cylindrical seat in which it bears, I am able, while using a form of the surface which can be produced with mathematical exactness by the ordinary machine tools for boring and turning, to secure a fit which will remain perfect for a long period, and which will allow the valve to be driven by the action of steam or other force directly applied to the ends without a necessity for intermediate mechanism.

Having now fully described my invention, what I claim as new therein, and desire to secure by Letters Patent, is as follows:

The master-valves D¹ D², operated by, and controlling, in turn, the action of the steam in throwing the main valve G, substantially as and for the purposes herein set forth.

In testimony whereof I have hereunto set my name in presence of two subscribing witnesses.

ALEXR. K. RIDER.
